UNITED STATES PATENT OFFICE.

GEORGE H. PROFFITT, OF WICHITA, KANSAS.

COMBINATION LID-FASTENER AND CARD-HOLDER.

1,341,588.

Specification of Letters Patent. Patented May 25, 1920.

Application filed November 5, 1919. Serial No. 335,856.

To all whom it may concern:

Be it known that I, GEORGE H. PROFFITT, a citizen of the United States, residing at Wichita, in the county of Sedgwick and State of Kansas, have invented certain new and useful Improvements in Combination Lid-Fasteners and Card-Holders; and I do hereby declare the following to be a full, clear, and exact description of the invention, such as will enable others skilled in the art to which it appertains to make and use the same.

This invention relates to an improved attachment for use in connection with the lid or cover of a receptacle such as a milk can and the principal object of the invention is to provide a device so constructed that the cover may be releasably but securely held in place and further to so construct this attachment that it may form means for engaging a card having an address shown thereon to retain the card in engagement with the cover.

Another object of the invention is to so construct this attachment that it may be used in connection with a milk can of any conventional construction, it simply being necessary to form openings in the cover and flared neck of the can and provide buttons upon the neck for holding the securing clip.

Another object of the invention is to so construct this attachment that the principal portion thereof may be formed of metal and wire cut and bent to assume the proper shape.

Another object of the invention is to so construct this attachment that it will comprise a comparatively few number of parts which will be simple in construction and strong and durable and not liable to easily get out of order or need repair.

This invention is illustrated in the accompanying drawings, wherein:

Figure 1 is a side elevation of the upper portion of a can having the cover held in place by means of the improved attachment.

Fig. 2 is a transverse sectional view taken along the line 2-2 of Fig. 1.

Fig. 3 is a top plan view of the cover.

Fig. 4 is a perspective view of one of the plates forming part of the attachment.

Fig. 5 is a perspective view of one of the latches used in connection with the attachment.

Fig. 6 is a perspective view of a clip for engaging the latch shown in Fig. 5.

Fig. 7 is a plan view of a name plate held in engagement with the cover by the attachment.

The can 10 is provided with a neck 11 which terminates in a flared mouth 12 having operatively disposed openings 13 formed therein and having outstanding studs 14. The cover 15 is provided with upstanding flared walls 16 and is provided with side 65 openings 17 which register with the openings 13 when the cover is put in place with the walls 16 fitting within the threaded mouth 12 of the can. The usual handle 18 is provided so that the cover may be easily 70 removed and put in place.

Plates 19 are secured to the inner faces of the walls 16 by rivets which pass through the openings 20 and through the walls 16 thereby firmly connecting the plates with 75 the inner or upper walls of the cover. The end portions of these plates are bent to provide retaining flanges 21 which are to engage the side portions of the address cards 22 and releasably retain the cards in place 80 when the cards are inserted as shown in Fig. 3 with the studs 23 fitting in the notches 24 formed in the upper end portions of the cards. A cover plate 25 which is similar in shape to the address cards will be 85 provided so that one of the cards may be covered. Therefore the cover of the milk can may be provided with two address cards one carrying the name of the producer and the second the name of the dairyman to 90 whom the milk is sent. By covering one of these cards with the cover plate 25 the second will be left disposed.

Latches indicated in general by the numeral 26 are provided at opposite sides of 95 the cover and are constructed and mounted as shown clearly in Figs. 4 and 5. Each latch is provided with a head 27 which is carried by a stem or shank positioned to extend through one of the openings 17 and having its free inner end portion provided with an opening 29 through which extends the pivot pin 30. This pivot pin 30 is mounted between the bearings 31 formed by cutting the plates 19 thus providing tongues having 100 the central portion cut out and the tongue bent back upon itself. When the cover is put in place as shown in Fig. 1 the latches extend through the openings 13 and may be engaged by the fasteners or clips one of 110 which is shown in detail in Fig. 6. Each of these clips are formed of resilient wire bent

intermediate its length to provide arms 32. The arms are bent at their connected ends toward each other and are then bent to extend downwardly from the 5 can thus providing a head forming a hand hold 33. The free end portions of the arms are bent inwardly to provide abutments 34 which prevented the clips from having sliding movement upon the studs 23 10 beyond the desired amount and are then bent to provide a socket 35 and guiding arms or fingers 36. The latch head 27 may be held in one hand and the clip then moved toward the latch and the neck or shank of the latch 15 will pass between the guiding fingers and into the socket 35. The cover will then be securely held in place and prevent it from accidentally working loose. When it is desired to remove the cover it is simply necessary to move the clips to release the latches 20 and the cover can then be grasped by the handle and removed. It will thus be seen that there has been provided a very efficient device for securing the cover of a milk can 25 and further that this device is so constructed that the address cards may be held in place and one of the address cards covered.

What is claimed is:

1. The combination with a receptacle having a neck terminating in a flared mouth, and a cover fitting within the flared mouth, the cover and mouth being provided with registering openings, of plates connected with the cover and having bearings positioned adjacent the openings in the cover, pivot pins carried by the bearings, latches having shanks mounted upon the pivot pins and extending through the openings of the cover and flared mouth and terminating in 40 an enlarged head, and means carried by the mouth for engaging the shank.

2. The combination with a receptacle having a neck provided with openings, and a cover fitting into the neck and provided 45 with openings registering with the openings of the neck, of bearing elements carried by the cover in opposed relation to the openings formed therein, pivot pins carried by the bearings, latches mounted upon the pivot 50 pins and extending through the registering openings, and clips slidably con-

nected with the neck and having arms bent adjacent their free end portions to provide guiding fingers and a pocket, the guiding fingers serving to engage 55 the outer end portions of the latches and guide the same into the pockets of the clips.

3. A receptacle provided with oppositely disposed openings, a cover fitting into the neck, and provided with openings registering with the openings of the neck, bearing members carried by the cover, latches connected with the bearing members and extending through the registering openings of the cover and neck, and securing 60 clips slidably connected with the neck in operative relation to the openings formed therein and each formed of a strand of resilient wire bent intermediate of its length to provide arms having their connected end 65 portions bent to extend outwardly from the neck and constitute an actuating handle, the free end portion of the arms being bent inwardly to provide abutments limiting sliding movement of the clips and being then 70 bent to provide a pocket for receiving the latch and having their free end portions bent outwardly to provide guiding fingers for engaging the latch and directing the same into the pockets.

4. A receptacle having a neck provided with openings, a cover having openings registering with the openings of the neck, latches connected with the cover and extending through the registering openings, studs 85 carried by the neck adjacent the openings, and clips each having arms extending in spaced relation for extending upon opposite sides of the studs, the free end portions of the arms being bent to provide abutments for engaging the studs for limiting sliding movement of the clip and being bent to provide a pocket and guiding fingers for engaging the outer end portion of their co-operating latch and directing the latch into 90 95 said pocket.

In testimony whereof I affix my signature in presence of two witnesses.

GEORGE H. PROFFITT.
